UNITED STATES PATENT OFFICE

BELLE STRUTHERS CAMERON, OF WIARTON, ONTARIO, CANADA

DESIGN FOR A HOSIERY DARNING FORM

Application filed May 4, 1931. Serial No. 39,716. Term of patent 7 years.

To all whom it may concern:

Be it known that I, BELLE STRUTHERS CAMERON, a citizen of Canada, residing at Wiarton, in the county of Bruce and Province of Ontario, Canada, have invented a new, original, and ornamental Design for Hosiery Darning Form, of which the following is a specification, reference being had to the accompanying drawing, forming part thereof.

In this drawing, the figure is a perspective view of a hosiery darning form showing my new design.

I claim:

The ornamental design for a hosiery darning form as shown.

BELLE STRUTHERS CAMERON.
